FASTENING MEANS FOR UNITING
BUILDING MEMBERS

Henry Hasenburger, Newark, N. J., and Harvey Wiley Corbett, New York, N. Y., assignors to Prebilt Housing Corporation, New York, N. Y., a corporation of Ohio

Application April 4, 1940, Serial No. 327,842

9 Claims. (Cl. 20—4)

This invention relates to wall construction for buildings, having particular reference to walls of the type composed of a plurality of factory fabricated panel units of definitive dimensions and configuration, the general object of the invention being to provide improved means for facilitating the assembling and uniting of said panel units in wall-producing order, whereby to produce a wall structure having substantial mechanical strength, low constructional costs and an improved external appearance.

Another object of the invention resides in the provision of an improved internal wall structure for buildings, wherein the wall structure is composed of a plurality of preformed panels arranged, when assembled, in a common plane, and wherein improved securing means are provided between the adjoining longitudinal edge portions of each pair of such panel units for the purpose of quickly uniting said units in secured association with an inwardly disposed supporting frame, the fastening means being of such character as to enable the panel units to be assembled or disassembled without marring or injuring the same and to be concealed from exterior view when the panels are in assembled or fastened relationship.

With these and other objects in view, which will appear as the description proceeds, the invention consists in the novel features of construction, combinations of elements and arrangements of parts hereinafter more fully described and pointed out in the appended claims.

In the accompanying drawing, forming a part of this specification and in which similar characters of reference denote like and corresponding parts throughout the several figures thereof:

Fig. 1 is a perspective view of the improved wall panel fastener comprising the present invention;

Fig. 2 is a horizontal sectional view taken through a wall structure in which the fastening means comprising the present invention is mounted;

Fig. 3 is a vertical sectional view taken through the wall structure on the plane indicated by the line III—III of Fig. 2;

Fig. 4 is a similar view on the line IV—IV of Fig. 2.

Referring more particularly to the drawing, the present invention is applicable to a wall structure composed primarily of preformed, factory fabricated wall panels of the type indicated at 1.

These panels may be formed from a number of different materials, such as pressed laminated plywoods, molded minerals of cementitious composition, asbestos, wood fiber compositions, re-

enforced plaster or plain wood. Such panels are available commercially and sold under a wide number of trade names and virtually all these panels may be adapted to the uses of the present invention for use in the forming of room side walls and ceilings.

As customary, the panels are provided with interfitting longitudinal edge portions, each panel having a shoulder extension 2 which acts as a seat for an inwardly offset tongue extension 3 formed with the complementary edge portions of an adjoining panel, a V groove 4 being formed by beveling the outer surface of the extension 2 and the corresponding surface of the adjoining panel, if desired. To adapt such panels to the present invention, it is only necessary to form therein, along one or more of its longitudinal edges, a longitudinal groove of the character indicated at 5.

The panels 1 are placed against a suitable supporting frame structure. Such a frame structure may comprise a pair of spaced rails 6—6, united by a spacer block 7, one of the rails 6 having its inner face longitudinally grooved as at 8, so that the grooves 5 and 8 will extend in parallel order.

The improved fastener comprising the present invention consists of a stamped metallic body having a rail-engaging section 9 and an angularly bent extension 10. Along its inner edge, the section 9 is formed with a laterally projecting flange 11, which is slidably received within the groove 8, while the extension 10 terminates at its outer edge portion in an inturned wedge-shaped flange 12. The fastener is slidable along the length of the inner face of the rail 6 with which it engages by virtue of the groove and flange construction 8 and 11 and is retained in a desired fixed position by the provision of a tongue 13 which is struck from the section 9 to extend in angular relation thereto, the outer end of the tongue being formed with a prong 14. The angularity of the tongue 13 is such that when the fastener is moved longitudinally on its rail 6 in one direction, the pronged end of the tongue slides freely over the opposite rail, but when the fastener is moved longitudinally in a reverse direction, the prong will engage with the rail 6a and bite into said rail to positively retain the fastener in a desired mounting position.

To secure the wall panels to this adjustable mounting bracket, there is provided a metallic fastening clip 15. Each of these clips is formed to include a body portion 16 which terminates along one edge in an angularly bent flange 17 formed to be slidably received between the ad-

joining edge portions of the panels 1 and to be received within the groove 5. The opposite edge of the body portion 16 of said clip is formed with a hook-shaped flange 18 which embraces the wedge flange 12 of the mounting bracket, the flange 18 having an angular mating with flange 12. The body portion 16 of said clip may also be provided with an offset lug 19 which acts as a finger or hammer engaging extension so that the clip may be readily grasped for effecting its movement on the flange 12.

It will be seen that in securing a panel in a mounted position on the supporting frame, the tongue extension 3 is first seated on the shoulder extension 2 of an adjoining mounted panel. The opposite longitudinal edge of the panel is then secured by placing one or more of the brackets on the rail 6 and fastening said bracket in its applied position by the use of the tongue 13. The clip 15 is then engaged with the flanged edge 12 of the bracket with the flange 17 of the clip positioned in the panel groove 5. By sliding the clip longitudinally along the flange 12, toward the higher portions of said flange, the clip will become frictionally wedged in firm holding engagement with the panel, supporting the latter securely against accidental displacement. This construction eliminates the necessity for nailing the panels in position, provides a fastening means which may be connected with the panel along any desired portion of its grooved longitudinal edge and, moreover, when mounted, the fastening means for the panel are concealed from exterior view. Similar convenience is obtainable in disassembling the wall-forming panels, accomplishing the result without in any way injuring or marring the panels for further use. The fastener enables wall panels to be assembled in rapid order, at low cost and without the use of nails or other fasteners which would tend to injure or mar the panels or cause the same to present an undesired appearance.

While the fastener set forth has been described as being particularly adapted for use in the mounting of wall panels, it is obvious that said fastener may be employed in other equivalent securing capacities in building construction. For example, it may be usually employed in connecting door and window trim frames to studding and the like or in uniting floor panels or sections to underlying joists. Other adaptations and structural modifications will be apparent to those skilled in the art and, therefore, the scope of the invention is defined in the following claims.

What is claimed is:

1. Wall construction comprising spaced studs, a plurality of wall-forming panels placed against said studs, one of said panels having one of its longitudinal edges formed with a groove, a bracket vertically adjustable between said studs, said bracket having a wedge-shaped flange, a movable slide member mounted on said bracket flange, and a lip formed with said slide member and receivable within the longitudinal groove of said panel.

2. Wall construction comprising a pair of spaced studs, a panel engaging with one of said studs, said panel having a groove in one of its longitudinal edges, securing means for connecting said panel with the stud with which it is engaged comprising a bracket member having sliding facial engagement with the side of the stud with which the panel member is engaged, a wedge-shaped flange formed with said bracket member, and a slide member arranged for longitudinal movement

on said bracket flange, said slide member being formed with a lip movably received within the groove in the edge portion of the panel member.

3. Wall construction comprising a pair of spaced vertical studs, one of said studs being longitudinally grooved, a fastening bracket having facial engagement with the grooved stud, a flange formed with said fastening bracket and slidably receivable within the groove of said stud, a resilient position retaining tongue projecting angularly from said bracket, said tongue being formed with a pronged outer end adapted for engagement with the complementary face of the ungrooved stud, a wedge-shaped flange formed with said bracket member, and a movable retaining member slidably mounted on said wedge-shaped flange.

4. A fastening device for building members comprising a bracket having a base-engaging facial portion, an angularly extending guide flange formed with one edge of said facial portion and receivable for longitudinal movement in a groove provided in an adjoining base member, an angularly extending securing tongue struck from said facial portion, said tongue having its outer end pointed for bracket holding engagement with a second base member spaced from the first-named base member, a wedge-shaped flange formed with the opposite edge portion of said bracket, and a slide element mounted on said wedge-shaped flange, said slide member having means formed therewith for uniting a separable building element with said bracket and associated base member.

5. A fastener for uniting building members comprising a relatively stationary base bracket, a wedge-shaped flange formed with said bracket, a slide member detachably positioned for longitudinal movement on said flange, said slide member having one edge thereof grooved to receive said flange, and a laterally offset flange formed with the opposite edge portion of said slide member, movement of said slide longitudinally of said wedge-shaped flange serving to vary the distance between said flanges.

6. A fastener for uniting building elements comprising a base-engaging bracket, said bracket having a flat base-engaging section formed along one edge with a perpendicularly disposed extension, said extension terminating at its outer end in an angularly bent wedge-shaped flange disposed in parallel relationship with the base-engaging section, and a slide element having along one edge thereof a hook-shaped flange engaged with said wedge-shaped flange, the opposite edge portion of said slide element being longitudinally flanged for engagement with a groove formed in an associated building element, movement of said slide longitudinally of said wedge-shaped flange serving to vary the distance between the flange on said slide and said bracket.

7. A fastener for uniting building members comprising a bracket having a body, a projection extending laterally from said body, a second projection extending in the opposite direction from said body, a wedge-shaped flange provided on said second projection and arranged in substantially parallel relationship with said body, a slider member mounted for longitudinal adjustment on said wedge-shaped flange, and a lateral projection provided on said slider, movement of said slider longitudinally of said wedge flange serving to move the projection on the slider toward and away from said body.

8. A fastener for uniting building members

comprising a bracket having a body, a projection extending laterally from said body, means provided on said body for engaging a portion of a wall frame and holding said projection in engagement with said wall frame, a second projection extending in the opposite direction from said body, a wedge-shaped flange provided on said second projection and arranged in substantially parallel relationship with said body, a slider member mounted for longitudinal adjustment on said wedge-shaped flange, and a lateral projection provided on said slider, movement of said slider longitudinally of said wedge flange serving to move the projection on the slider toward and away from said body.

9. A fastener for uniting building members

comprising a bracket having a body, a projection extending laterally from said body, a second projection extending in the opposite direction from said body, a wedge-shaped flange provided on said second projection and arranged in substantially parallel relationship with said body, a slider member mounted for longitudinal adjustment on said wedge-shaped flange, a lateral projection provided on said slider, movement of said slider longitudinally of said wedge flange serving to move the projection on the slider toward and away from said body, and means formed on said slider for facilitating the movement thereof on said flange.
